(57) **CLAIM**

The ornamental design for a pressure gauge as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a pressure gauge according to the present invention.

FIG. 2 is a front view of the pressure gauge of FIG. 1.

FIG. 3 is a rear view of the pressure gauge of FIG. 1.

FIG. 4 is a top view of the pressure gauge of FIG. 1.

FIG. 5 is a bottom view of the pressure gauge of FIG. 1.

FIG. 6 is a right side view of the pressure gauge of FIG. 1; and,

FIG. 7 is a left side view of the pressure gauge of FIG. 1. The broken lines are included for purposes of illustrating portions of the pressure gauge that form no part of the claimed design.
